ARROWHEAD

William Doonan, 711 E. De Soto, Ypsilanti, Mich.

Filed June 18, 1959, Ser. No. 56,419

Term of patent 14 years

(Cl. D30—1)

FIG. 1 is a top plan view of an arrowhead embodying my new design;

FIG. 2 is a side elevational view thereof; and

FIG. 3 is a front end view thereof.

The characteristic features of my design for the arrowhead disclosed reside in the blades having the configuration shown.

I claim:

The ornamental design for an arrowhead, as shown and described.
